UNITED STATES PATENT OFFICE

CARLOS SALZEDO, OF NEW YORK, N. Y., ASSIGNOR TO LYON & HEALY, INC., OF CHICAGO, ILLINOIS, A CORPORATION OF ILLINOIS

DESIGN FOR A HARP

Application filed February 14, 1931. Serial No. 38,653. Term of patent 14 years.

To all whom it may concern:

Be it known that I, CARLOS SALZEDO, a citizen of the United States of America, residing at New York city, in the county of New York and State of New York, have invented a new, original, and ornamental Design for Harp, of which the following is a specification, reference being had to the accompanying drawing, forming a part thereof.

The figure is a view in perspective of a harp, showing my new design. The rear of the sound board is of conventional shape.

I claim:

The ornamental design for a harp, substantially as shown and described.

CARLOS SALZEDO.
